CLAIM

The ornamental design for a sectional sofa, as shown and described.

DESCRIPTION

FIG. 1 is a front perspective view of a sectional sofa in accordance with the invention;

FIG. 2 is a right side front view of the sectional sofa of FIG. 1;

FIG. 3 is a right side rear view of the sectional sofa of FIG. 1;

FIG. 4 is a left side rear view of the sectional sofa of FIG. 1;

FIG. 5 is a left side front view of the sectional sofa of FIG. 1;

FIG. 6 is a top view of the sectional sofa of FIG. 1; and,

FIG. 7 is a bottom view of the sectional sofa of FIG. 1.

The broken lines in the figures illustrate the portions of the design that form no part of the claimed design.
